COKE OVEN APPARATUS

Lorenz S. Herrmann, Jr., Mount Lebanon Township, Allegheny County, Pa., assignor to The Koppers Company of Delaware, a Corporation of Delaware

Application January 28, 1930. Serial No. 423,974

11 Claims. (Cl. 137—144)

My invention relates to coke-oven apparatus and particularly to reversing boxes for selectively controlling the supply of combustible media to, and the flow of waste gases from, coking retort ovens.

In the operation of coke-oven batteries, it is desirable to simplify the apparatus for controlling the supply of fuel gas, such as producer gas, and air for heating the ovens of the battery and for controlling the flow of waste gases from the ovens to the stack. In the case of complicated systems for controlling the reversing boxes for controlling the flow of the several gases, it is possible that breakage of a portion of the controlling mechanism may cause an explosive mixture either in the reversing boxes or in the regenerators which will either burn therein or may cause an explosion with resultant damage to the structure of the battery.

In accordance with the present invention, I have provided a series of reversing boxes, certain of which operate as air boxes in one direction of flow or as waste gas boxes when the flow of gases is reversed. Certain other reversing boxes are arranged to supply either producer gas or air to the battery or to convey waste gases when the flow is reversed.

By means of a relatively simple mechanism, I am enabled to arrange the various boxes in a system wherein all of the boxes may be caused to reverse the flow of gases therethrough by the actuation of their controlling levers in the same direction by means of a single cable or controlling device.

The levers are connected to the valves controlled thereby by means of relatively simple link-and-lever mechanisms, each of which permits one valve to close and positively opens another valve. Lost-motion connections in these mechanisms permit these operations in reversible sequences.

The details of my invention will be described in connection with the accompanying drawings, in which

Figure 1 is a view in transverse vertical section of a portion of a coke-oven battery embodying my invention;

Fig. 2 is a view, partially in section and partially in side elevation, of one form of reversing box constructed in accordance with my invention, associated parts of a coke-oven structure being shown in vertical section;

Fig. 3 is an enlarged view of the clutch mechanism and certain associated parts;

Fig. 4 is a similar view of another form of reversing box;

Fig. 5 is a view, partially in plan and partially in horizontal section, of certain reversing boxes of a series in operative relation to a coke-oven battery; and

Fig. 6 is a view, partially in end elevation and partially in vertical section, of the apparatus of Fig. 5, parts being broken away.

Referring particularly to Fig. 1, a coke-oven battery 1, only a portion of which is shown, comprises a foundation 2, a side wall 3 and a top 4 that is provided with the usual charging holes 5 extending into coking chambers 6, only one of which appears in the drawings. Horizontal brickwork 7 separates the coking chambers 6 from the regenerators 8, one of which appears in the drawings, and which are provided with sole flues 9.

Coke-oven gas is supplied to the battery by means of a main 11 and producer gas is supplied through a larger main 12. A reversing box 13, which is connected to the sole flue 9 through the side wall 3, is connected to the producer gas main 12 and is also connected by a vertical duct 14 to a waste gas main 15 that is connected to the usual stack.

Products of distillation are collected in the usual manner through a gas offtake opening 17 and an ascension pipe 18 that is connected to a collecting main 19.

Referring to Fig. 2, the reversing box 13 that is shown in enlarged detail therein comprises a hollow casting 20 having a producer gas valve 21 for controlling the connection of the reversing box to the producer gas main 12. It is provided, also, with a waste-gas valve 22 for controlling the connection to the vertical duct 14.

An air damper 23, which is pivotally mounted on the top of the casting 20, is adapted to be operative when the box 13 is used as an air box, as in case coke-oven gas is used as a fuel. When the reversing box 13 is used as a gas box, the damper 23 is clamped in its closed position by means of a clamp 24, which is best shown in Fig. 5.

The valves 21 and 22 are operated by means of a mechanism comprising an operating lever 25 that is pivotally mounted on a bracket 26. As best shown in the reversing box 13 on the extreme right in Figs. 5 and 6, the lever 25 has a lost-motion connection to a link 27 that is pivotally connected to a rocker arm 28 that operates a rock shaft 29. A quadrant 30 that is carried by the other end of the shaft 29 is connected

by means of a chain 31 or other flexible device to the waste-gas valve 22. As illustrated in the box, Figs. 2 and 6, the waste-gas valve 22 is in its uppermost or open position.

5 The lever 25 is provided with an extension 32 that has a pivotal lost-motion connection to a link 33 and the latter is similarly pivotally connected to an arm 34 that is mounted on a rock shaft 35. When the reversing box 13 is arranged 10 for operation as a gas box, the rock shaft 35 is connected to the gas valve 21 by means of a yoke 36 connected to the shaft 35, a clutch pin 37, a relatively long arm 38, a link 39, an arm 40 and a rock shaft 41 which carries a quadrant 42. A 15 chain 43 connects the quadrant 42 to the valve 21.

When the reversing box 13 operates as an air box, the shaft 35 is connected to the damper 23 by the clutch pin 37 which engages an arm 44.

20 As shown in Fig. 3, the clutch pin 37 is shiftable to the right, by means of a handle 45, to connect the shaft 35 to the damper 23 or to the left to connect the shaft 35 to the arm 38 and thereby determine the operation of the box as an 25 air box or a gas box, as the case may be.

As arranged in the drawings, the box 13 is adapted to operate as a gas box, the damper 23 being clamped in its closed position and disconnected from the shaft 35.

30 A reversing box similar to the box 13 that has just been described is the reversing box 47 that is located at the extreme left-hand portion of Figs. 5 and 6. The arrangement of the link-and-lever mechanisms for operating the several 35 valves is arranged in what may be termed a left-hand assembly with respect to the arrangement of the reversing box 13, which may be termed a right-hand assembly.

40 The various parts are similar to those of the reversing box 13, except that the operation of the lever 25 produces opposite effects. For example, it is noted that the producer gas valve 21 is open in the case of reversing box 47, while the same valve is closed in reversing box 13, the 45 lever 25 occupying the same position in each case. Also, the waste-gas valves 22 of the respective boxes are in opposite positions, that of reversing box 47 being closed and that of reversing box 13 being open.

50 Reference may now be had to Fig. 4, in which an air box 51 is shown in enlarged detail. The air box illustrated in Fig. 4 corresponds to the air box 51 adjacent the box 13 in Figs. 5 and 6. It comprises a hollow casting 52 with no connection to the gas main 12. The lever 25 is connected to the waste gas valve 22 by mechanism that is identical with that described in connection with reversing box 13 and similar numerals are employed to designate the corresponding 60 parts.

The air dampers 23 are operated by a mechanism that is similar to that of reversing box 13 for operating the rock shaft 35. The latter is, however, replaced in the present case by a relatively short shaft 53 that is connected to the air damper 23 by an arm 44.

70 An air box 54 that is adjacent to the air box 51 is similar to the latter except that the operating mechanism therefor is transposed in order that its air damper 23 may be open when the air damper of air box 51 is closed and vice versa, the operating levers 25 being in similar positions. The waste-gas valves 22 of the pair of air boxes 75 occupy opposite positions.

75 The castings 55 and 56 for connecting the main

body portion of the several reversing boxes to the sole flues of the regenerators are of similar construction. In order that the reversing boxes may occupy proper positions with respect to the sole flues, it is necessary that these castings be made in rights and lefts, however, in order to avoid the buck-stays 57, which support the side walls of the battery. These castings are interchangeable between the air boxes and the gas boxes and reduce the number of kinds of boxes required.

80 The operation of the system comprising air boxes and gas boxes, a typical portion of which is shown in Figs. 5 and 6, will be readily understood. A cable or rod 58, which extends along one side of the battery and is actuated by the usual time-controlled reversing mechanism, is connected by pairs of clamps 59 spaced by a yoke 60 to all of the levers 25 of the various gas and air boxes.

85 It may be assumed that the battery to which the system is connected is in operation and that the boxes 47 and 54 are arranged to supply gas and air respectively as indicated by the legends G and A. It may be assumed, also, that the boxes 51 and 13 are conveying waste gases from their 90 respective regenerators, as indicated by the legend WG. The several valves, including the air dampers, of the various boxes will occupy the positions in which they are shown.

95 When the rod 58 is actuated to the left to correspondingly actuate the levers 25 about their points of pivotal support, the gas valves 21 are first closed by relatively quick action of the quadrant 42 and its actuating mechanism and a period of about 3 or 4 seconds elapses before the 100 waste-gas valves 22 of the same reversing boxes 13 and 47 or the air valves of boxes 51 and 54 begin to open.

105 The lost-motion connections permit the open air and waste-gas valves to partially close before the similar closed valves begin to open. Before the closed positions of the previously open air and the waste-gas valves are reached, however, the ends of the lost-motion connections are 110 reached and the mechanism operates to partially open the air and the waste-gas valves for operation in the opposite direction in order that the draft through the battery is never completely 115 closed at the reversing boxes. The closing movements of the former air and waste-gas valves 120 are completed after the latter valves are slightly opened and the partially opened valves are then 125 actuated to their completely open positions.

130 In the case of the previously closed gas valves 21, they do not begin to open until a period of 3 or 4 seconds has elapsed after the closure of the waste-gas valves 22 in the same reversing boxes 13, whereupon they open with a relatively quick movement.

135 The direction of flow in the battery and in the several reversing boxes is now reversed and the functions of the boxes are those indicated by the respective legends in dotted lines thereon.

Upon the succeeding reversal, the positions of the several parts are reversed in the same manner 140 as described in connection with the other reversal and the parts again occupy the positions in which they are shown.

145 In case coke-oven gas is used as a fuel, all of the reversing boxes will be used as air boxes, half of the boxes supplying air while the other boxes are conveying waste gas. In order to adapt the boxes 47 and 13 shown in Figs. 5 and 6 for coke-oven gas operation, the clutch pins 37 are shifted to disengage the corresponding arms 38 and to 150

engage the arms 44 for connecting the rock shafts 35 to the air dampers 23, the clamps 24 of the latter being released. In this arrangement, the boxes 47 and 54 will operate simultaneously to admit air 5 while the boxes 51 and 13 convey waste gas and, upon reversal, the latter boxes both admit air while the other boxes convey waste gas.

From the foregoing, it will be apparent that I have provided a simple arrangement whereby a 10 single cable or rod may operate a series of reversing boxes for controlling the flow of air and producer gas into a coke-oven battery and the flow of waste gases therefrom. The controlling levers are positively connected to each of the valve mechanisms for actuating them to their open positions and the latter are permitted to close by force of 15 gravity.

Among the advantages of my invention are the simplicity and ruggedness of the parts which have 20 the operating characteristics necessary to operate the valves in proper sequence. The parts have definite relations and they may be readily assembled in proper arrangement. Any error in assembly may be readily detected and easily 25 corrected.

The foregoing and other advantages will be apparent to those skilled in the art of the construction and operation of coke-oven batteries.

I claim as my invention:

30 1. A valve mechanism for coke ovens comprising two passageways for fuel gas and air respectively, a valve for each passageway, an oscillatable lever, a shaft oscillatable with said lever and means for selectively connecting said shaft to the one or the other of said valves.

35 2. A valve mechanism for coke ovens comprising two passageways, two valves for respectively controlling said passageways, a single oscillatable lever, a shaft connected thereto, and means comprising a clutch for selectively connecting said shaft to the one or the other of said valves.

40 3. A valve mechanism for coke ovens comprising two passageways, two valves for respectively controlling said passageways, a single oscillatable lever, a shaft connected thereto, a member carried by said shaft, and means comprising an adjustable pin carried by said member for connecting the latter to the one or the other of said valves.

45 4. A valve mechanism for coke ovens comprising passageways for fuel gas, air and waste gases respectively, a single oscillatable lever, a shaft oscillatable therewith, and means for connecting said lever to the valve for waste gases and for selectively connecting said shaft to the fuel gas valve or the air valve.

50 5. A valve mechanism for coke ovens comprising two valves for respectively controlling the flow of gaseous media through said mechanism, and means operable in one direction for reversing the 55 positions of both of said valves, said means comprising a single oscillatable lever and a quadrant connected to each of said valves and having a lost-motion connection to said lever.

60 6. A valve mechanism for coke ovens comprising two valves for respectively controlling the flow of gaseous media through said mechanism, one of said valves being closed while the other is open, and oscillatable means for reversing the positions of said valves, said means comprising an operating lever, a quadrant connected to each of said valves and a link-and-lever mechanism for con-

necting said lever to each of said quadrants and for permitting lost motion between said lever and said quadrants.

7. A valve mechanism for coke ovens comprising two valves for respectively controlling the flow of gaseous media through said mechanism, one of said valves being closed while the other is open, and oscillatable means for reversing the positions of said valves, said means comprising an operating lever, a quadrant flexibly connected to each of said valves to permit their closing by force of gravity, and a link-and-lever mechanism for providing a lost-motion connection between said lever and each of said quadrants whereby certain independent movements of said valves are permitted.

8. A valve mechanism comprising a plurality of each of fuel gas valves, air valves and waste gas valves, certain of each of which valves are open while the other valves are closed, means for controlling said valves to reverse their positions comprising a plurality of levers occupying similar positions and each lever being connected to a plurality of valves, link-and-lever mechanisms for connecting said levers to said valves and a single member for actuating all of said levers.

9. A valve mechanism comprising a plurality of each of fuel gas valves, air valves and waste gas valves, certain of each of which valves are open while the other valves are closed, means for controlling said valves to reverse their positions comprising a plurality of levers occupying similar positions and each lever having a lost-motion connection comprising a link-and-lever mechanism to each of a plurality of valves and a single member for actuating all of said levers.

10. Valve mechanism comprising a plurality of reversing boxes for coke ovens said reversing boxes being arranged in a row, each of said boxes having a plurality of valves for controlling the direction of flow of gaseous media therethrough, certain of said valves being positioned for inflow of gaseous media while the other valves are simultaneously arranged for outflow thereof, a single operating lever for each reversing box, link-and-lever mechanisms for connecting the levers to the valves of the respective reversing boxes, and a single member for oscillating all of said operating levers to thereby simultaneously reverse the flow of gaseous media through all of said reversing boxes in said row.

11. Valve mechanism comprising a plurality of reversing boxes for coke ovens, said reversing boxes being arranged in a row, each of said boxes having a plurality of valves for controlling the direction of flow of gaseous media therethrough, certain of said valves being positioned for separate and simultaneous inflow of fuel gas and air while the other valves are arranged for outflow of waste gases, a single operating lever for each reversing box, link-and-lever mechanism for connecting the levers to the valves of the respective reversing boxes, and a single member for oscillating all of said operating levers to thereby simultaneously reverse the flow of gaseous media through all of said reversing boxes in said row to cause those previously conducting fuel gas or air to conduct waste gases and those previously conducting waste gases to conduct fuel gas or air.

LORENZ S. HERRMANN, JR.
